UNITED STATES PATENT OFFICE.

ELMER A. MAKER, OF SWANSEA, MASSACHUSETTS.

PLOW ATTACHMENT.

1,263,690.

Specification of Letters Patent. Patented Apr. 23, 1918.

Application filed January 15, 1916. Serial No. 72,300.

To all whom it may concern:

Be it known that I, ELMER A. MAKER, a citizen of the United States, residing at Swansea, in the county of Bristol and State 5 of Massachusetts, have invented certain new and useful Improvements in Plow Attachments, of which the following is a specification.

This invention has relation to certain new 10 and useful improvements in plow attachments and has for its primary object, the provision of a harrow attachment for plows of conventional form.

The invention has for another object, the 15 provision of a plow attachment which will be of simple construction and operation and may be readily attached to the mold board and handles of the plow and adjusted as required.

20 A further object of the invention resides in the provision of a harrow attachment for plows which will be composed of the minimum number of parts and which may be readily adjusted with respect to the plow 25 point and mold board.

With the above and other objects in view, the invention resides in the novel construction, combination and arrangement of parts as will be hereinafter more specifically set 30 forth, pointed out in the claims and shown in the drawings in which:

Figure 1 is an elevation of a conventional form of plow with my attachment applied to the same, and

35 Fig. 2 is a top plan of the principal portions of the attachment.

Referring more particularly to the drawings, in which similar reference characters designate corresponding parts throughout 40 the several views, 1 designates the mold board and 2 the handles of a plow of conventional form to which my attachment is applied, the bracket arm 3 being secured to the rear corner of said mold board 1 and 45 having its free rear end twisted, as shown at 4 and suitably bifurcated to receive the forward ear 5 of the body 6 of the harrow rake, a suitable pivot pin 7 being extended through the ear 5 and the end 4 of said bracket arm 3.

50 The main portion of the body 8 is offset downwardly and has its rear edge 8 bent downwardly to support the upper bent ends 9 of the arcuate harrow teeth 10, secured to 55 said edge 8 by suitable securing members 11.

Pivoted between the pair of upstanding ears 12 carried upon the upper face of the body 6, by a suitable pivot pin 13, is the lower end of an adjusting rod 14, the upper end of which is pivoted to the adjusting lever 15. The adjusting lever 15 is in turn pivoted to the rack segment 16 mount 1 in a suitable manner as indicated at 17, upon the handles 2. The lever 15 is of conventional form and carries a locking rod 18 having 60 one end normally engaged with the teeth of the rack segment 16, by means of a spring 19 engaged therearound, the usual release finger 20 being pivoted to the lever 15 and connected to the rod 18 to withdraw the latter from the rack segment 16.

In use, the angle of the body 6 and harrow teeth 10 with respect to the mold board 1 and the point of the plow as well as the ground may be readily regulated by adjustment of the lever 15 which, as will be readily understood may be automatically locked in 70 adjusted position by releasing the finger 21 and permitting the spring 19 to act upon the rod 18.

75 While the preferred embodiment of the invention has been shown and described, it will be understood that many minor changes in the details of construction and arrangement of parts may be made within the scope 80 of the appended claims without departing from the spirit of the invention or sacrificing any of the advantages of the same.

85 What is claimed is:

1. A harrow attachment for a plow comprising a short, relatively straight bracket arm fixed on the mold board of the plow and projecting rearwardly therefrom in a horizontal direction, a harrow member pivotally supported by said bracket arm, said harrow member comprising a body formed with a forwardly projecting ear pivotally connected to the end of said bracket arm and a rearwardly extending terminal flange and downwardly and rearwardly convexed teeth attached to said flange, and means on the plow handles for adjusting the position of said harrow member.

90 2. A harrow attachment for a plow, comprising a harrow fork body having a depending edge, teeth secured to said edge, an ear projecting from the opposite edge of said body, means for pivotally connecting said ear to a rigid portion of the plow, means pivoted to said body to adjust the 95 100 105 110

angle of the same and the angle of said teeth with respect to the plow and surface over which the latter is to travel, and means for controlling the last mentioned means.

- 5 3. A harrow attachment for a plow comprising the combination with the mold board and handles of a plow; of a bearing arm mounted upon said mold board, a harrow rake pivoted to said bearing arm, an ad-

justing lever mounted upon said handles, 10 and connections between said lever and said harrow rake.

In testimony whereof I affix my signature in presence of two witnesses.

ELMER A. MAKER.
